UNITED STATES PATENT OFFICE.

JOSEPH KOMOROUS, OF RIVERSIDE, ILLINOIS, ASSIGNOR TO PARISIAN NOVELTY COMPANY, OF CHICAGO, ILLINOIS.

SUPPORT FOR THERMOMETERS.

Application filed February 13, 1922. Serial No. 536,049.

To all whom it may concern:

Be it known that I, JOSEPH KOMOROUS, a citizen of the United States, and a resident of Riverside, county of Cook, and State of Illinois, have invented certain new and useful Improvements in Supports for Thermometers, of which the following is a specification.

My invention relates to supports for thermometers, or the like, and has for its object the provision of an improved construction of this character, which is durable and efficient in use and capable of economical manufacture.

Other objects will appear hereinafter. The invention consists in the combinations and arrangements of parts hereinafter described and claimed.

The invention will be best understood by reference to the accompanying drawings forming a part of this specification, and in which—

Fig. 1 is a front elevation of the invention,

Fig. 2 is a section taken on line 2—2 of Fig. 1,

Fig. 3 is a section taken on line 3—3 of Fig. 1, and

Fig. 4 is a section taken on line 4—4 of Fig. 2.

As illustrated in the drawings, 1 represents a facing plate preferably of sheet metal, over which is stretched a sheet of heat insulating material 2, to the outer face of which is secured a thermometer tube 3. The thermometer tube 3 is fastened in position by means of staples 4, which have their inner ends clinched under the plate 1. This construction is fully set forth in my divisional application, Serial No. 430,850, filed December 15, 1920, and needs no further explanation here.

The support per se and its related structure, forms the subject matter of this application. The facing plate 1, as stated, may be of any desired material and may have its outer surface ornamented or utilized for any suitable purpose. A backing member 5 of any suitable material, preferably of cardboard, is placed in rear of the

plate 1 and is secured in position thereagainst by means of the edges 6, which are spun or upset over the edges of the backing member 5, thus securing the members 1 and 5 together in an efficacious manner. 55

A recess is provided between the members 1 and 5, such recess opening outwardly through the member 5, the object of such recess being to permit of the insertion of any suitable supporting member therein. 60 As shown in the drawings, such recess consists of the groove 7 disposed adjacent the edges of the member 5, such groove in this instance connecting notches 8, provided in the edges of the member 5. A supporting member 9 is inserted in the notches 8 and is held from disengagement therefrom by contact with the upset edges 6 of the plate 1. By this arrangement, two members are secured together in a novel manner, and supporting means provided therefor which are simple in construction and efficient in use. 65

While I have illustrated and described the preferred form of construction for carrying my invention into effect, this is capable of variation and modification without departing from the spirit of the invention. I, therefore, do not wish to be limited to the precise details of construction set forth, but desire to avail myself of such 70 variations and modifications as come within the scope of the appended claims. 75

Having described my invention, what I claim as new and desire to secure by Letters Patent is:

1. The combination of a facing member and a backing member, said members being secured together, there being a groove extending between said members and having its ends opening outwardly through one of said members; and a supporting member operatively mounted in said groove, substantially as described.

2. The combination of a facing member and a backing member, said members being secured together by turning the edges of one member over the corresponding edges of the other member, there being notches in the edge of said backing member; and a supporting member operatively mounted in 90 95 100

said notches and bearing against said turned edges, substantially as described.

3. The combination of a member and another member secured thereto by turning the edges of said other member over the edges of said first member; and a support consisting of a loop, there being notches in the edge of said first member, said loop being placed in said notches and held in

place by said turned edges, substantially as described. 10

In testimony whereof I have signed my name to this specification in the presence of two subscribing witnesses.

JOSEPH KOMOROUS.
